SAFETY REVERSIBLE WINDOW

Louis I. Alperin, Scranton, Pa.

Application July 17, 1945, Serial No. 695,581

4 Claims. (Cl. 20—49)

1

My invention relates broadly to windows and more particularly to an improved arrangement of hardware for converting existing double hung window sashes into a swinging reversible sash window.

One of the objects of my invention is to provide an improved construction of hardware which may be applied to double hung window sashes for converting such windows into swinging reversible sash windows.

Another object of my invention is to provide a simplified construction of double hung reversible window sash arrangements in which standard sliding sashes are converted into sliding and swinging sash arrangements with simplified hardware for maintaining the sashes in a particular tilted position.

Still another object of my invention is to provide a simplified arrangement of combined weather strip and latch for tilttable double hung slideable windows in which the latch becomes effective to maintain the sashes of the window in particular angular positions as the sashes are tilted in selected vertical positions.

Still another object of my invention is to provide a construction of pivot means for the swinging sashes of a double hung window in which the pivot means becomes effective to maintain the tilttable sashes in a particular position to which the sashes are moved before tilting.

A further object of my invention is to provide a construction of hardware for double hung slideable sashes of tilttable windows wherein pivot means are provided which become effective to grip the side frames of the window in the position in which the sashes are tilted for maintaining the sashes in such selected position.

Other and further objects of my invention reside in the construction of improved hardware for double hung reversible window sashes with associated interlocking weather stripping in which:

Figure 1 is a front elevational view of a converted double hung reversible window sash arrangement embodied in my invention and showing the interlocking weather stripping and the operators therefor associated with each of the window sashes; Fig. 2 is a vertical sectional view taken through the window frame taken on line 2—2 of Fig. 1 and showing the double hung sash in full line and the manner in which the sashes may be tilted to dotted line position; Fig. 3 is a horizontal transverse sectional view taken through the pivoted position of one of the double hung slideable and swingable window sashes substantially on line 3—3 of Fig. 1 and illustrating the pivot members in retracted position permitting vertical sliding movement of the window sash; Fig. 4 is a view similar to the view shown in Fig. 3 but representing the sash tilted at an

2

angular position and showing the manner in which the pivot means are projected simultaneously at opposite sides of the sash for gripping the sash in a predetermined tilted position with respect to the sash; Fig. 5 is a fragmentary vertical sectional view of the left side frame portion of a slideable or a slideable and tilttable sash and showing the association of the interlocking weather stripping, the operator therefor and the pivot means for the sash, the view being taken substantially on line 5—5 of Fig. 8 and illustrating the projected interlocking position of the weather stripping permitting vertical movement only of the sash; Fig. 6 is a view similar to the view illustrated in Fig. 5 but showing the weather stripping retracted preparatory to a tilting movement of the sash; Fig. 7 is a vertical sectional view taken on line 7—7 of Fig. 6 and showing the pivot means in a position for vertical sliding movement of the sash; Fig. 8 is a transverse sectional view taken substantially on line 8—9 of Fig. 5, the view being an enlarged section of one side of the sash illustrated in Fig. 3 in which the sash is free for vertical movement; Fig. 9 is a transverse sectional view taken substantially on line 9—9 of Fig. 5; Fig. 10 is a transverse sectional view taken substantially on line 10—10 of Fig. 6; Fig. 11 is a foreshortened vertical sectional view taken through the window sash and associated weather stripping and pivot means substantially on line 11—11 of Fig. 6; Fig. 12 is a fragmentary vertical sectional view taken through the weather stripping, the associated guide means therefor and the pivot means substantially on line 12—12 of Fig. 5; Fig. 13 is an elevational view of the operator for controlling the projection and retraction of the weather stripping, the view being taken on line 13—13 of Fig. 5; Fig. 14 is a fragmentary vertical sectional view of the left side of the frame of a tilttable sash and illustrating the projection of the pivot means for gripping the tilttable sash in a selected vertical position in which the sash is tilted, the view being an enlargement of one side of the sash shown in Fig. 4; Fig. 15 is a perspective view of the weather stripping, the pivoted means, and the coacting longitudinally extending sash strip associated with each side of the sash frame; Fig. 16 is a perspective view showing the longitudinally slotted side portion of each of the slideable sashes with the associated pivoted means therefor; Fig. 17 is a side elevational view of the pivoted means provided at each side of the slideable sash; Fig. 18 is an elevational view of the hardware shown in Fig. 17; Fig. 19 is a vertical sectional view through the hardware of Figs. 17 and 18, the view being taken on line 19—19 of Fig. 18; Fig. 20 is an elevational view of the metallic insert which is mounted in the longitudinally extending sash strip for receiving the sash pivoted means; Fig. 21

is a vertical sectional view taken through the metallic insert of Fig. 20 on line 21—21 thereof and Fig. 22 is a transverse sectional view through the metallic insert of Fig. 20 on line 22—22 thereof.

My invention is directed to a simplified arrangement of hardware for converting existing double hung window sashes to swingable or tiltable window sashes. The hardware is readily installed either in existing double hung slidable windows or supplied with new installations of sashes in building construction. In applying the hardware of my invention to existing double hung window sashes, the upper and lower sashes are removed from the window frame and the sashes cut down at each side thereof approximately one-half to three-fourths of an inch. A narrow slot or groove is then mortised into the edge of each sash for receiving a projectable and retractable weather stripping, an operator therefor and a central pivoted guide. A longitudinally extending strip extending the length of the sash is then applied at each side of the sash. The strip serves as a connector for the sash cords, a coacting weather strip element and as a carrier for the hardware constituting the pivoted means for the sash. The strip carries a liner in the form of a recessed cup which has a diametrically extending slot therein aligned with the coacting weather strip groove in the sash strip. The liner serves as a bearing means for cam members carried by the hardware constituting the pivoted means for the sash. When the sash operates in a vertical sliding direction the cam members are aligned with the diametrical slot in the liner permitting vertical sliding movements of the sash. However, when the sash is moved to a selected position with respect to the window frame and then angularly tilted the cam members of the hardware slide against the faces of the liner projecting the hardware transversely at opposite sides of the sash gripping the sides of the window frame and maintaining the sashes in a selected tilted position.

Referring to the drawings in detail, reference character 1 designates the lower sash and reference character 2 designates the upper sash of a double-hung window, in which the sashes are slidable in stiles 3 and 4, with sash strips 5 and 6 guided by the stiles. The opposite extreme edges of the window sashes represented by lower sash 1 are cut down in width to receive the sash strips 5 and 6, the thickness of which compensates for the material removed from the edges of the sash thereby enabling the sash to be slidable within the longitudinally extending stiles of the window frame and swingable transversely of the stiles.

The opposite edges of the sashes are mortised as represented at 7 for receiving projectable and retractable weather stripping 8, cushioned against coil springs 9 and 10, which are arranged in aligned sockets 11—12 and 14—15 in the inner edge of the weather stripping 8 and the mortise 7 of window sash 1.

The window sash 1 is slotted at 18 to allow the passage of connecting member 17 which is secured to the rear of weather stripping 8. Connecting member 17 is provided with an inwardly projecting portion having an angularly disposed slot 18 therein. The slotted portion 18 of the connecting member 17 projects beyond the inner edge of the window sash 1 and is engaged by a transverse pin 19 carried by the manual operator 20.

The manual operator 20 is centrally recessed at

21 for the passage of the inwardly projecting end of the connecting member 17, whereby upward movement of the operator 20 projects weather stripping 8 from the mortised recess 7, as shown in Fig. 5, whereas, downward movement of operator 20 retracts weather stripping 8 into the mortised recess 7, as shown in Fig. 6.

Weather stripping 8 is centrally cut away, as represented at 22, for permitting the weather stripping 8 to extend on opposite sides of the hardware plate 23 which is secured centrally of the edge of window sash 1. The hardware 23 carries an integral inwardly extending socket 24, of polygonal or square section. A similar socket is provided at each edge of the window sash and serves to receive the projecting end or stud 25 of the journaling hardware, shown more particularly in Figs. 17—19.

The journaling hardware comprises a circular plate 26, connected to the central polygonal or square stud 25, which enters the socket 24 at each side of the window sash. The plate 26 carries diametrically opposed cam members 27 and 28 which are movable on an orbit of approximately 90 degrees. The journaling hardware is mounted within a recessed liner 29 shown more particularly in Figs. 20—22, embedded within sash strip 5. Sash strip 5 has a central opening 30 therein adapted to receive the recessed liner 29. The recessed liner 29 is cup-shaped in section having a pair of lugs 31 and 32, extending on diametrically opposite sides thereof and serving to secure the recessed liner in position with respect to the sash-strip 5, as shown. The recessed liner 29 has a diametrically extending slot 33 therein which is aligned with the groove 34 in the sash-strips, into which the weather stripping 8 is adapted to project.

The cam members 27 and 28 extending from plate 26 normally project through the slot 33 in liner 29 and groove 34 in the sash-strips when the window sash is maintained in a vertical position for upward and downward sliding movement in the stiles. This is accomplished by the registration of the polygonal or square stud 25 with the correspondingly shaped socket 24, as represented in Figs. 3, 5, 6, 7 and 8. However, when the sash is tilted through an angular position which rotates cam members 27 and 28, against the inner faces of a recessed liner 29, as represented in Figs. 4 and 14, this results in the ejection of the plates 26 of the oppositely arranged journaling hardware simultaneously in opposite directions. The studs 25 are each slideable or adjustable transversely of the sash in the sockets 24. This results in the frictional gripping of the opposite sides of the frame of the double-hung window inner faces which I have represented at 35. Thus the window sashes after being adjusted to a selected vertical position may be substantially locked or restrained in position by tilting of sashes at an angle, thereby spreading the plates 26 of the journaling hardware in opposite transverse directions for gripping the inner faces 35 of the window frame.

The sash strips 5 and 6 are each apertured at 39 and grooved at 37 to receive the knotted ends of the sash cords 38 which operate over pulleys 39 through the frame of the window and connected to sash weights 40, which balance the raising and lowering of the window sashes.

The window sashes carry suitable glazing represented by glass panes 41. The double-hung window sashes when in closed position may readily have the weather stripping 8 which is carried

thereby ejected into the aligned grooves 34 by moving the operators 20 upwardly as represented in Figs. 5 and 9 for thereby rendering the window tight against the entry of wind, rain, dust, sand or snow.

Throughout the specification I have restricted the explanation to one side of the window frame, as it will be understood both sides are symmetrical and that the explanation relates equally well to both sides. It will also be understood that tilting movement of the window sashes after vertical adjustment thereof to selected positions automatically locks or fixes the sash in the position to which it is adjusted by reason of the simultaneous outward movement of the plates 26 of the journaling hardware members. That is to say, the hardware members establish a tight fit within the window frame when the sashes are in tilted position but assume a loose fit when the sashes are in vertical sliding position.

While I have described my invention in one of its preferred embodiments, I realize that modifications and changes may be made and I intend no limitations upon my invention other than may be imposed by the scope of the appended claims.

What I claim and desire to secure by Letters Patent of the United States is as follows:

1. Hardware for controlling the position of double-hung window sashes in longitudinally extending stiles in a window frame for composite translatory and angular movement of the sashes with respect to the window frame comprising strip members slidable in the stiles of a window frame and disposed at opposite edges of translatory and angularly movable window sashes, cup-shaped members recessed into central positions in said strip members, diametrically opposite lugs secured to said cup-shaped members and fastened to transverse positions on said strip members, plate members each having a stud thereon, said plate members being disposed in said cup-shaped members and said studs extending into opposite edges of the window sashes and turnable therewith, said studs being positionally adjustable with respect to said window sashes and means interposed between said cup-shaped members and said plate members whereby angular movement of said window sashes operates to transversely displace said plates for frictionally engaging the window frame and securing the sashes in the selected angular positions.

2. Hardware for controlling the position of double-hung window sashes in longitudinally extending stiles in a window frame for composite translatory and angular movement of the sashes with respect to the window frame comprising strip members slidable in the stiles of a window frame and disposed at opposite edges of translatory and angularly movable window sashes, cup-shaped members recessed into central positions in said strip members, diametrically opposite lugs secured to said cup-shaped members and fastened to transverse positions on said strip members, plate members each having a stud thereon, said plate members being disposed in said cup-shaped members and said studs extending into opposite edges of the window sashes and turnable therewith, said studs being positionally adjustable with respect to said window sashes and cam members interposed between said cup-shaped members and said plates for transversely displacing said plates as said sash members are tilted for frictionally engaging the window frame and securing the sashes in a selected angular position.

3. Hardware for controlling the position of double-hung window sashes in longitudinally extending stiles in a window frame for composite translatory and angular movement of the sashes with respect to the window frame comprising strip members slidable in the stiles of a window frame and disposed at opposite edges of translatory and angularly movable window sashes, internally disposed polygonally shaped centrally disposed sockets carried by opposite edges of said sashes, weather stripping resiliently disposed for projection and retraction in the edges of said sashes and extending symmetrically on opposite sides of said sockets, operators carried by the window sashes and movable to control the projection and retraction of the weather stripping with respect to said sashes, said strip members being longitudinally grooved for receiving said weather stripping when said weather stripping is projected with respect to said sashes, means carried by said strip members and extending into said polygonally shaped sockets for pivoting said sashes and means associated with the aforesaid means for transversely displacing said first mentioned means as said sashes are angularly shifted for frictionally engaging the window frame and securing the sashes in selected angular positions.
4. Hardware for controlling the position of double-hung window sashes in longitudinally extending stiles in a window frame for composite translatory and angular movement of the sashes with respect to the window frame comprising strip members slidable in the stiles of a window frame and disposed at opposite edges of translatory and angularly movable window sashes, cup-shaped members recessed into said strip members, said cup-shaped members being slotted diametrically in a direction longitudinally of said strip members, said strip members being grooved in alignment with the diametrical slots in said cup-shaped members, projectable and retractable weather stripping carried by the opposite edges of said window sashes and projectable and retractable with respect to the grooves in said strip members, hardware members each including a plate and stud, one of said plates being centered within each of said cup-shaped members, cams on said plate and angularly movable in engagement with the cup-shaped members to a position within the slotted portions of the cup-shaped members, the studs on said hardware members projecting into opposite edges of said sashes and serving as pivotal mounting means therefore and slidable transversely with respect thereto as said plate members shift from a position in which said cams engage said cup-shaped member to a position in which said cams are aligned with the slots in said cup-shaped members.
